SCREW DRIVER

Levi E. Bailey, Owosso, Mich.

Application August 9, 1945, Serial No. 609,806

2 Claims. (Cl. 145—50)

1

This invention relates to screw drivers, and particularly to a screw driver having the blade so formed that the screw may be driven when the handle is rotated on its axis and when disposed at an angle to the axis of the screw to function as a lever.

Screw drivers have heretofore been manufactured to drive and set a screw through the rotation of the screw driver about its axis and the axis of the screw. Screw drivers having various sizes of blades were employed for operation on different sizes of screws so that the screw could be solidly set by the twisting of the screw driver about its axis.

The present invention embodies the use of a blade having a curved end which varies in radius so as to be able to contact screws of different sizes. The screw is driven by the rotation of the handle about its axis and set when the axis of the handle is offset at an angle to the axis of the screw to function as a lever. The sides of the blade may diverge or converge to the arcuate end portion depending upon the size of screws on which the screw driver is to be employed. The blade is welded, brazed or otherwise secured to a shank which may be set in a handle or which may be removably secured in a holder disposed in the handle to provide a screw driver having a plurality of blades.

The main object of this invention is to provide a screw driver with a blade having an end portion disposed on a varying arc which is capable of engaging a screw with the axis of the screw driver aligned with the axis of the screw and disposed at an angle thereto.

Another object of this invention is to provide a handle with a holding element in which the shanks of a set of screw driver blades may be disposed in removably fixed relation thereto.

A further object of the invention is to provide a handle with a plurality of screw driver blades which vary in shape and size but which have arcuate ends on the screw-engaging portions so that the screw driver may be tilted relative to the axis of the screw and maintained in driving relation therewith.

Other objects and features of novelty of the invention will be specifically pointed out or will become apparent when referring, for a better understanding of the invention, to the following description taken in conjunction with the accompanying drawing, wherein:

Figure 1 is a view in elevation of a screw driver embodying features of this invention;

Fig. 2 is an enlarged sectional view of the

2

structure illustrated in Fig. 1, taken on the line 2—2 thereof;

Fig. 3 is an enlarged, broken sectional view of the structure illustrated in Fig. 2, taken on the line 3—3 thereof;

Fig. 4 is a perspective view of a screw driver blade, similar to that illustrated in Fig. 1, showing a further form which it may assume;

Fig. 5 is a view of a screw driver blade with the screw-engaging portions thereof disposed in different relation to each other;

Fig. 6 is a view of a screw driver blade similar to that illustrated in Fig. 4, disclosing the arcuate end thereof applied directly to the screw driver shank;

Fig. 7 is a perspective view of a screw driver blade similar to that illustrated in Fig. 5, showing a further form which the invention may assume;

Fig. 8 is a broken view in elevation of a screw driver similar to that illustrated in Fig. 1, showing a further form of the invention, and

Fig. 9 is a view of a screw driver having screw-engaging portions on opposite ends thereof.

Referring more specifically to Figs. 1, 2 and 3, a screw driver 10 is illustrated comprising a handle 11 which may be made of wood, plastic or other suitable material. An aperture 12 is provided on the central line of the handle from the blade end thereof in which a shank-supporting element 13 is secured and maintained against rotation by a pin 14 which extends therethrough and through the handle. A ferrule 15 may be provided about the blade-receiving end of the handle 11 to strengthen the end and to prevent it from being damaged and weakened from use. The shank-supporting element 13 has an aperture 16 and a sloping surface 17 on the inner end thereof. The sloping surface 17 is machined on the element 13 through an aperture 18 in its wall. When the element is to be embedded in moulding material, a sleeve 19 may be disposed over the element to cover the aperture 18 for preventing the moulding material from entering the aperture 16 during the moulding operation.

The blade 21 of the screw driver is welded or otherwise secured to a shank 22 which has a diameter to snugly fit the aperture 16 of the element 13. The end of the shank 22 is notched at 23 and provided with a sloping surface 24 which engages the sloping surface 17 of the element 13 to provide an outward bias to the shank 22 which forms a friction lock for retaining the shank 22 in the element.

50

The blade 21, as illustrated in Figs. 1, 2 and 3, is constructed from sheet stock of hardenable material of a thickness to be insertable in slots of a number of screws of different sizes so that only a small number of the blades are required for a large range of screw sizes. The blade has a flat arcuate end portion 26 struck on the radius of considerably greater length than the radii of the arcuate corner portions 27. It is contemplated that the screw will be driven in the normal manner through the engagement of the arcuate portion 26 with the slot in the screw head by rotating the handle 11 about its axis on the axis of the screw. When the torque requirement for rotating the handle has increased an appreciable amount, the handle is then tilted to have the arcuate corner portion 27 rest in the slot in the screw head with the handle at an angle to function as a lever. The screw is set with a pulling or pushing force rather than a twisting one when the handle is disposed at an angle, with very little energy. The arcuate portion 27 being of a smaller radius, will be maintained within the slot in the screw head and will not damage the surrounding surface as the screw is set.

In view of the fact that only a minimum amount of torque is applied through the handle portion 11, it will be noted that the handle is left smooth without the usual ridges and indented portions heretofore provided so as to permit the operator to apply a substantial torque without slippage. In the present type of screw driver, the torque application is at a minimum so that no difficulty is experienced due to the slipping of the operator's hand on the handle when a smooth surface is employed.

In Fig. 4, a further type of screw driver blade is illustrated, that wherein the blade 31 converges toward the driving end 32 to reduce the width of the arcuate end portion which contains a flat curve 26 which blends in with the arcuate corner portions 27 of smaller radii. The blade functions in the same manner as the blade 21 with the exception that it is employed to drive and set smaller screws than those with which the blade 21 would be employed. It will be noted that the width of the end portion 33 opposite the end 32 is the same as the end portion 33 on the blade 21, both dimensions being the same as the diameter of the ferrule 15 so as to be in continuation thereof.

Additional types of screw driver blades are illustrated in Figs. 5, 6 and 7, wherein the shank portions 22 have different types of blade ends. In Fig. 5, a body portion 35 in extension of the shank 22 has a blade 36 thereon which has a flat arcuate end face 26. Stub body portions 37 and 38 extend in aligned relation on each side of the body portion 35 having blade ends 39 and 41 respectively. The blade ends 39 and 41 are disposed in planes at right angles to each other and are provided with the flat arcuate end portions 26 which project within the slot of the screw head. A screw may be engaged by the blade end 36 and may be thereafter set by the blade ends 39 or 41, or any of the blade ends may be employed for driving and setting a screw.

In Fig. 7, the shank 22 has a body portion 42 provided with a head 43 disposed at right angles thereto in T-relation therewith. Blade ends 39 and 41 are provided on the head 43, the same as on the stub body portions 37 and 38 of Fig. 5. The structure is similar to that of Fig. 5 with the exception that the blade end 36 is eliminated.

In Fig. 6, the shank 22 is illustrated as being provided with a conventional screw driver body 45 having the end thereof provided with a flat arcuate face 26 which permits the screw driver to be tilted so that the axis of the screw driver is at an angle to the axis of the blade, while a firm driving connection is provided between the screw driver end and the walls of the slot in the screw head.

In Fig. 8, a further form of the invention is illustrated, that wherein a handle 47 supports a shank 48 of a screw driver blade 49 in permanent fixed relation. The material of the handle 47 may be plastic which is moulded about the handle as well as the portion 51 at the rear of the blade to securely anchor the shank and blade within the handle against rotation and separation. Further anchorage may be provided by the projecting tabs 52 on the shank provided thereon in the conventional manner. It is also within the purview of the invention to drive the shank 48 into the end of a handle made of wood, plastic or other material. It is to be understood that the blade 49 may be similar to the blades illustrated in Figs. 1 to 7.

A further form of the invention is illustrated in Fig. 9, wherein a plate 55 is provided with an end 56 of greater width than the small end 57. The arcuate surfaces 26 and 27 are provided on each of the end portions so as to provide a screw driver which may be employed for driving large or small screws, the same as the blades 31 and 21 in Figs. 1 and 4 if combined into a single plate. The plate 55 may be made any size and a screw driver substantially the size as illustrated in the figure may be carried in the pocket and be available to drive conventional types of screws. It is to be understood that larger types may be utilized for production work where heretofore different sizes of screw drivers had been employed. The single plate or blade may be retained in the hand of the operator and reversed end for end for driving different sizes of screws without the necessity of changing screw drivers, as has been the practice.

The screw driver of the present invention is unique in that the driving end is of varying arc formation having a flat arcuate end which engages the slot in the screw when the screw driver is rotated with its axis aligned with the axis of a screw for initially driving the screw. The corner arcuate portion 27 engages the slot with the handle at a substantial angle to the axis of the screw to function as a lever for applying a force for finishing the driving operation and for thereafter setting the screw. The handle may be provided with a shank-receiving element so that various types of blades may be employed with a single handle to form a screw driver set. The element in the handle is provided with a sloping surface engageable by a sloping surface on the end of the blade shank so that a lock is provided for retaining the shank and blade in fixed relation therewith. The handle may be moulded about the shank or about the shank-receiving element out of mouldable plastic material conventionally employed in the art.

What is claimed is:

1. A screw driver including, in combination, a handle, a shank in the handle, and a screw driver blade extending from one end of said shank, the screw engaging end of the blade being of varying arcuate shape at the end and corner portions, the end portion being of greater radius than the radii of the arcuate portions at the cor-

ners thereof, the side edges of the blade sloping relative to said shank, the centers from which the arcuate end and corner portions are scribed falling within the blade.

2. A screw driver including, in combination, a 5 blade having sloping sides to provide a screw-engaging end, said screw-engaging end having the shape of a varying arc with the end portion being struck on a greater radius than the radii of the arcuate corner portions, the centers from 10 which the arcs are scribed falling within said blade.
